UNITED STATES PATENT OFFICE.

HERMAN E. BROWN, OF SAN FRANCISCO, CALIFORNIA.

WASHBOILER.

1,132,431.

Specification of Letters Patent. Patented Mar. 16, 1915.

Application filed October 10, 1911. Serial No. 653,845.

To all whom it may concern:

Be it known that I, HERMAN E. BROWN, a citizen of the United States, residing at San Francisco, in the county of San Francisco and State of California, have invented 5 a new and useful Washboiler, of which the following is a specification.

This invention relates to improvements in wash boilers, which, however, is equally applicable for several other utilities.

10 The invention has for its object to facilitate the washing operation also to expedite the same, as well as to render the washing action effective, and in the minimum time.

15 A further object is to carry out the aforesaid ends in a simple and inexpensive manner.

20 The invention consists of certain instrumentalities and features substantially as hereinafter fully disclosed and defined by the claim.

25 In the accompanying drawing, illustrating the preferred embodiment of my invention wherein it will be understood that various changes and modifications may be made as relates to the details of the construction and arrangement of the parts without departing from the spirit of my invention,—Figure 1 is a vertical longitudinal 30 section through the apparatus in position in a wash boiler, said section being taken on the line A—B Fig. 2. Fig. 2 is a section on line C—D Fig. 1. Fig. 3 is a perspective view of one of the conductors. Fig. 4 is a 35 perspective view of one of the valves or slides. Figs. 5 and 6 are perspective views of two forms of caps or closures for use in connection with the apparatus.

40 In practising my invention I employ an oblong water-containing receptacle 1, preferably adapted to conform to, and be received within an ordinary wash boiler, as 2, having the usual closure 3, said receptacle, in practical use, resting upon the bottom of 45 the boiler. The receptacle 1 has a longitudinally sub-dividing partition 4, provided with numerous orifices or perforations 5, said receptacle itself also having numerous perforations or orifices 6 in its bottom and 50 top surfaces, said perforations or orifices providing, as is apparent, for the general water-circulation under the usual ebullition action, as the device, with its contained water, is subjected to the action of heat, as 55 when the boiler, within which it may be disposed, is placed upon a stove or heater. Said

receptacle has also centrally of its upper surface an upstanding oblong tubular neck-like extension or collar 7, opening therethrough and communicating with the interior water-receiving chamber; also at one end of said upper surfaces is a like neck or tubular extension 8 also communicating with said interior water-chamber, these passages or neck-members providing for the upward 60 passage of the water currents under the ebullition-action, as well understood, in effecting the washing-operation.

A tubular upper-end closed member or conductor 9 is suitably pivoted or hinged as 70 at 10 to each of the neck or collar members 7 and 8 to further upwardly direct the water-currents and promote circulation, also to deliver said water-currents at an elevated point to the fabrics or articles being treated or 75 washed for effectually cleansing the latter. Within the central tubular member or conductor 9 is suitably soldered, or otherwise secured, an edgewise arranged brace or braces 9^a to prevent liability of collapsing or 80 bending said conductor by contact therewith of the fabrics while undergoing the washing operation. Said conductors or tubular members have suitably applied to their upper ends finger-bolts or rings 11, for conveniently placing the same in position and removal thereof, as may be desired.

The conductors 9 are each provided with two series or rows of perforations 12 arranged at different altitudes for accordingly delivering the water-currents, under 90 the ebullition action, to the fabrics and for varying the height of such water-current delivery, one of each row of perforations of each conductor being adapted to be controlled by a slide or valve 13 for aiding in effecting that end, which will be readily appreciated. Each valve or slide 13, which is preferably in the form of a plate, inclined downwardly at its end-edges as at 14 and 95 provided at its upper edge with an outstanding horizontal ledge 15, for conveniently engaging the same by hand, is received at its said downwardly, inclined end-edges within, and between outstanding groove-forming 100 members or guides 16 on the conductor.

In using a single conductor or stack, one or the other of the stacks or conductors 9 may be removed from its respective neck-member or nipple and the same be substituted by a cap or closure 17, the use of either 110 of the two forms of which as shown in Figs.

5 and 6, depends upon which of the two conductors or stacks it may be desired to remove. It is also apparent that this device may be readily adapted for several utilities, 5 as for instance for canning fruits, and vegetables, and for steam-cooking.

In using the apparatus it is placed within a boiler and the fabrics to be cleaned are placed upon the receptacle 1. The boiling 10 water will be expelled through the uncovered ports in the conductors and against the fabrics so as to thus thoroughly clean them. The dirt separated from the fabrics will settle to the bottom of the boiler.

15 It will be seen that, by hingedly connecting the conductors to the top of the receptacle 1, they can be swung downwardly onto the top of said receptacle when the device is not in use and can, therefore, be compactly 20 stored and conveniently shipped. As the fabrics to be cleaned are placed on receptacle 1 and between the two conductors 9, it will be seen that it is necessary to employ only one hinge for the end conductor 9, the 25 fabrics serving to press the conductor outwardly toward the end of the boiler 2. In order to maintain the central conductor 9 in a vertical position, however, it is necessary to provide a hinge connection at each side 30 of said conductor, as shown in Fig. 1. The pintle of one of these conductors is removable however, as will be apparent by referring to Fig. 2 wherein the pintle has been illustrated at 10'. When the pintles of 35 both hinges of the middle conductor are in place, said conductor will be held against

swinging movement but however, by withdrawing the removable pintle 10', the conductor can be caused to swing down onto the top of the receptacle 1.

40

What is claimed is:—

An attachment for wash boilers including a water receptacle adapted to be placed upon and to completely cover the bottom of a boiler, said receptacle having a central up-standing neck extending transversely there-of to points close to the sides of the receptacle, a tubular conductor having its lower end normally surrounding the neck, said conductor being extended transversely above 50 the receptacle, a hinged connection between each side of the conductor and the top of the receptacle, the neck being extended between said connections, one of the connections including a removable pintle, said conductor being adapted, when the pintle is removed, to swing downwardly onto the top of the receptacle and between the ends thereof, the removable pintle, when in position, constituting means for holding the conductor against downward swinging movement, said conductor having water outlets 55 for directing water toward both ends of the receptacle.

60

In testimony that I claim the foregoing 65 as my own, I have hereto affixed my signature in the presence of two witnesses.

HERMAN E. BROWN.
